UNITED STATES PATENT OFFICE.

WILLIAM R. FISCHER, OF ST. PAUL, MINNESOTA, ASSIGNOR TO KOEHLER & HINRICHES CO., OF ST. PAUL, MINNESOTA, A CORPORATION OF SOUTH DAKOTA.

COOLER FOR BEVERAGES.

1,258,101.

Specification of Letters Patent.

Patented Mar. 5, 1918.

Application filed August 21, 1916. Serial No. 115,976.

To all whom it may concern:

Be it known that I, WILLIAM R. FISCHER, a citizen of the United States, residing at St. Paul, in the county of Ramsey and State 5 of Minnesota, have invented new and useful Improvements in Coolers for Beverages, of which the following is a specification.

Its object is to provide a cooler for beverages designed to be easily and thoroughly 10 cleansed and which is readily adaptable to contain several beverages in varying quantities.

A further object is to provide a sanitary cooler of this kind having a number of effluent 15 pipes and a plurality of removable and interchangeable containers adapted to be easily replaced in the cooler and designed to form leak-proof connections with said effluent pipes.

20 In the drawings, Figure 1 is a side elevation of my improved cooler, a part thereof being broken away to show in section its interior; Fig. 2 is a plan view of the cooler with the cover removed; and Fig. 3 is an 25 enlarged detail sectional view of a portion of the bottom of one of the receptacles and a portion of the bottom of the tank.

Referring to the drawing, which illustrates an embodiment of my invention, I 30 have used the reference numeral 10 to indicate a tank having spaced side walls 11 and 12 and spaced bottoms 13 and 14. This tank is supported upon suitable standards 15 and is supplied with a cover 16 having a handle 35 17 thereon. A number of faucets 18, 19, 20 and 21 are fixed upon the lower front side of the cooler and pipes 22, 23, 24 and 25, respectively connected with said faucets, pass rearwardly between the bottoms 13 and 14, 40 thence upward through the inner or false bottom 13. The end of the last named pipe 25 lies flush with the bottom 13, but the remaining pipes extend above it and have threaded ends or nipples 26, opening into 45 the beverage receptacles or cans 27, preferably cylindrical in form, which may be of metal, glass or stone. Said nipples 26 are each supplied with lock nuts 28 arranged upon and bearing tightly against opposite 50 sides of the bottom 13. Each receptacle has an outlet 29 in its bottom opening into a nipple 26, which outlet 29 is supplied with a flange 30 secured upon the bottom of said receptacle, said flange having a threaded bore 55 to receive the nipple 26. A support is also

formed upon the bottom of each receptacle and may comprise a perforated depending rim 32, as shown, or a plurality of legs, or other suitable supporting devices. In placing a receptacle within the tank 10, the 60 flange 30 is connected to the nipple 26 in one of the effluent pipes by turning the receptacle until the rim 32 bears upon the bottom 13. The lower end of the flange 30, which is beveled internally, is designed to contact 65 with a soft lead gasket 33 on said nipple simultaneously, or substantially so, with the engagement of said rim 32 with the bottom of the tank. If, after continued use, a groove is worn in the gasket 33 by the sharp edge 70 34 of the flange 30, and the rim 32 strikes the bottom 13 before said flange is seated upon the gasket 33, the bottom 13 of the tank, or the bottom of the receptacle, or both, will spring to permit further rotation 75 of the receptacle until said flange is firmly seated upon said gasket. It will be seen that this method of installing a receptacle within the tank is easily accomplished; that the connection between said receptacle and its 80 effluent pipe is very secure; that said receptacle is firmly and rigidly supported; and that it may be easily removed for cleaning or other purposes.

To prevent sediment from entering the 85 effluent pipe 25, when water is drawn from the tank for use, I provide a hollow mushroom-shaped strainer, the stem 35 thereof being fitted in the open end of the pipe 25. The enlarged upper end 36 of said strainer 90 is formed with small perforations 37 to admit water and said end is located slightly above the bottom 13 to prevent the entrance of sediment, which may have settled to the bottom. This strainer may be withdrawn 95 from the pipe 25, thus permitting the user to drain the tank.

The space within the tank surrounding the receptacle is adapted to contain water and ice to cool the contents of the receptacles. Various sized receptacles may be supplied with the cooler, but the threaded bores in the flanges 30 are uniform, thereby permitting the substitution and interchanging of said receptacles. This is advantageous because at different seasons, greater or less supplies of certain beverages are demanded, and the capacity of the tank for holding cooling liquid and ice may be increased by removing certain of the recep- 100 105 110

tacles or substituting smaller ones; and it is also apparent that the ease with which the tank and receptacles may be cleaned by removing the latter, and the ability to flush the effluent pipes with water from the tank when the receptacles are removed, will encourage the maintenance of the cooler in a sanitary condition.

Having described my invention, what I claim as new and desire to protect by Letters Patent, is:

1. In a cooler, a tank, a plurality of effluent pipes leading from the tank, said pipes being supplied with threaded ends projecting upward into the tank, lock nuts on said threaded ends bearing against opposite sides of said bottom, a plurality of receptacles, each having an internally threaded flange on the bottom thereof, said receptacles being adapted to be interchangeably attached to said projecting threaded pipes, a support on each receptacle designed to rest upon the bottom of the tank, a gasket on the threaded end of each pipe arranged to be engaged by the flange of a receptacle simultaneously with the engagement of the receptacle support with the bottom of the tank, and faucets for said pipes.

2. In a cooler, a tank, an effluent pipe having a faucet thereon, said pipe being supplied with a threaded end passing upward through the bottom of the tank, lock nuts on said pipe bearing against opposite sides of said bottom, a receptacle, an internally threaded flange on the bottom of said receptacle to receive the threaded end of said pipe, the lower end of said flange being beveled internally to form a sharp annular bearing, and a gasket resting upon one of said lock nuts and providing a seat for said annular bearing.

3. In a cooler, a tank, an effluent pipe having a faucet thereon, said pipe being supplied with a threaded end passing upward through the bottom of the tank, a receptacle, an internally threaded flange on the bottom of said receptacle to receive the threaded end of said pipe, the lower end of said flange being beveled internally to form a guide for said flange when applied to the pipe and also to form a sharp annular bearing, and a gasket on said pipe forming a seat for said annular bearing.

Whereof, I have hereunto subscribed my name to this specification.

WILLIAM R. FISCHER.
